UNITED STATES PATENT OFFICE.

CHARLES GRAFF, OF NEW YORK, N. Y., ASSIGNOR TO GRAFF, WASHBOURNE & DUNN,
OF NEW YORK, N. Y., A CORPORATION OF NEW YORK.

DESIGN FOR A DISH.

47,751.

Specification for Design.

Patented Aug. 24, 1915.

Application filed July 16, 1913. Serial No. 779,400. Term of patent 14 years.

To all whom it may concern:

Be it known that I, CHARLES GRAFF, a citizen of the United States, residing at New York, county of New York, State of New York, have invented a new, original, and ornamental Design for a Dish, of which the following is a specification, reference being had to the accompanying drawing, forming a part thereof.

In the drawing, which illustrates the design as embodied in a teapot, Figure 1 is a perspective view of the dish, and Fig. 2 is a horizontal section through the body of the dish with the handle and spout removed.

As shown in the drawing, the body A of the dish is formed of panels 1, which are convex in horizontal section, so as to produce dull corners on the meeting lines 2 of the

convex curves, and the same feature is carried through the inwardly extending rim B and base C of a dish having these portions, as in the teapot shown, the desired shape vertically being secured by curves forming surfaces concaved vertically. In dishes having a cover, as in the teapot shown, the same design is carried into this, the cover D shown being formed of panels 3 convex horizontally and meeting in dull lines 4 and with inward curves forming surfaces concave vertically.

I claim:—

The ornamental design for a dish, as shown and described.

CHAS. GRAFF.
